DOOR CLOSER

William J. Keene, Chicago, Ill., assignor to Chicago Spring Hinge Company, Chicago, Ill., a corporation of Illinois

Application February 4, 1937, Serial No. 123,943

2 Claims. (Cl. 16—80)

This invention relates to devices for effecting the automatic closing of hinged doors, such as the doors of cold storage rooms, refrigerators, and the like.

5 In one well known type of automatic door closer there is vertically journaled on that member of the door frame on which the door is hinged a shaft, fast on which is a laterally extending horizontal arm that overlies the front 10 side of the door, and a spring, usually of the torsion type, is connected at one end to the shaft and, when put in tension, tends to turn the latter in a direction to force the arm against the front side of the latter so as to oppose the 15 opening movement of the door and, if the latter is open, push the door to closed position. An improved door closer of this general type forms the subject matter of my pending application filed July 18, 1936, Serial No. 91,272.

20 The arms used in door closers of this type are long members usually extending to or past mid-width of the door, and consequently stick out a considerable distance into the room space when the door is open. The arm, under some 25 circumstances, may be left in "open" or extended position even though the door be closed, in which case the projecting arm constitutes a nuisance, if not a source of danger.

An object of the present invention has been 30 to provide a stout, rugged and efficient door closer that will avoid the above-noted objection, and this object I accomplish by an improved construction wherein the spring impelled arm is substantially shortened and, instead of acting on 35 the front or face of the door, acts on the hinged edge thereof at a point sufficiently in advance of the hinge axis of the door to oppose the opening movement of the latter, and, when the door is open, urge it to closed position.

40 Still other objects and attendant advantages of the invention will be apparent to persons skilled in the art from the following detailed description, taken in connection with the accompanying drawing wherein I have presented 45 an illustrative embodiment of the invention, and in which—

Fig. 1 is a front elevation of the door closer, shown mounted on a vertical member of the door frame; the figure also showing a fragment of 50 the hinged edge portion of the door.

Fig. 2 is a horizontal section on the line 2—2 of Fig. 1.

Fig. 3 is a vertical axial section through the 55 closer, taken on the line 3—3 of Fig. 1.

Fig. 4 is a horizontal section on the line 4—4 of Fig. 1.

Fig. 5 is a perspective detail of a locking collar forming a part of the door closer.

Referring to the drawing, 10 designates a vertical side member of a door frame, and 11 designates a door of substantial thickness, as indicated in Fig. 2, such as is commonly used on cold storage-chambers, refrigerators, and the like. To the face of the vertical frame member 10 and the 10 adjacent edge of the door 11 are secured hinge brackets 12 and 13 respectively, through which extends the usual hinge pintle 14. Two or more of such hinges spaced vertically of the door are, 15 of course, used.

On the front faces of attaching bases, or filler blocks 15 attached to the frame member 10 are attached upper and lower brackets 16 and 17 respectively. The upper bracket 16 is formed with three spaced shelves 18, 19 and 20, in which is journaled a short vertical shaft designated as 20 an entirety by 21. This shaft has a lower round portion 22 having a bearing in the shelf 20, an intermediate reduced round portion 23 having a bearing in the shelf 19, and an upper further 25 reduced round portion 24 having a bearing in the shelf 18. Between the bearing portions 22 and 23 is a polygonal portion 25 on which is non-rotatably mounted the hub 26 of a short forwardly extending arm 27 that, as best shown in 30 Fig. 2 lies crosswise of the door 11 opposite the hinged edge of the latter. Between the hub 26 and the bracket shelf 19 is interposed a locking collar 28 shown in isolated detail in Fig. 5. The purpose of this collar is to lock the hub 26 in 35 engagement with the polygonal section 25 of the shaft, but permit it to be raised out of engagement, by withdrawal of the collar 28, when it is desired to shift the hub into a new position of engagement with the shaft, as, for instance, when 40 tensioning the torsion spring, later referred to. The collar 28 is removably attached to the bracket shelf 19 by means of an apertured lug 29 on the collar engaged with a notch in the edge of the shelf 19, and a fastening screw 30. 45

To the lower end of the shaft 21 is anchored the upper end of a torsion spring 31, the lower end of which is anchored to the lower bracket 17. Surrounding and housing the spring 31 is a tube 32 attached to the upper and lower brackets as 50 by screws 33.

Mounted on a squared portion 34 of the shaft 21 is a peripherally notched disc 35, with which cooperates a manually operated detent pawl 36.

Mounted on the front portion of the hinged 55

edge of the door 11 is a bracket 31, in which is journaled a roller 38 so positioned that the arm 27 has an anti-friction bearing thereon. This roller is not indispensable to the operation of the device, but is preferably employed to avoid frictional wear on the front corner of the door itself.

The parts having been assembled as shown in Fig. 3, and the pawl 36 being retracted from the disc 35, the spring 31 is placed under tension by 10 swinging the arm 27 to the right, viewing Fig. 2, and then engaging the pawl 36 in a notch of the disc 35; the arm 27 may then be set in a new angular position relatively to the shaft by withdrawing the locking collar 28, raising the hub of 15 the shaft off the polygonal portion 25, turning it to a new position, reengaging it with the polygonal section 25, this operation being repeated as many times as necessary to properly tension the spring, and then replacing the locking collar 28.

20 A fully opened position of the door is indicated by dotted lines in Fig. 2, and the door may be locked in such an open position by manually engaging the pawl 36 with a notch of the detent disc or ratchet 35. Owing to the comparatively 25 short leverage of the arm 27, a correspondingly heavy or stiff spring 31 is employed. However, it will be observed that the axis of the pintles 14 of the door hinges is so related to the axis of the shaft 21 on which the closer arm swings, that 30 when the door is opened, the point of engagement of the door roller 38 with the arm 27 progressively moves outwardly on the arm. The effective lever arm length of the closer arm 27 is thereby progressively increased so that the force 35 required to open the door does not increase in direct proportion to the increase in tension of the spring as it is wound up. This is a desirable arrangement in that it avoids excessive resistance to movement of the door in opening 40 direction, especially when the door nears its full open position.

As before stated, the described structure, by imparting a thrust on the hinged edge of the door instead of on the front or face of the door, permits the use of a short arm, which need not project beyond the plane of the face of the door, thus providing a very compact and unobtrusive door closer. The structural details of this device, except as to the parts and arrangement 50 thereof whereby a door-closing thrust is imparted to the hinged edge of the door, are substantially identical with corresponding parts in my aforesaid application Serial No. 91,272.

I claim:

55 1. In combination with a door frame and a

refrigerating room door vertically hinged at one edge thereof on a vertical member of said frame so as to open outwardly, said door being hinged in such a manner that a substantial portion of the thickness of said door projects outwardly beyond 5 the hinge axis, a bracket mounted on said vertical frame member, a vertical shaft journaled in said bracket, an arm carried by said shaft and extending laterally therefrom and crosswise of said portion of the thickness of the hinged 10 edge of the door which projects outwardly beyond said hinge axis, means on the hinged edge of said door outwardly of said hinge axis for engaging said arm, said arm being of such short length as not to project substantially beyond the 15 plane of the outside of the door, and a spring tending to turn said shaft in a direction to cause said arm to bear on said roller to thereby effect closing of the door, the axis of said shaft being so located relative to said hinge axis that when 20 the door is opened, the point of engagement between said arm and said means moves outwardly to progressively increase the lever arm length of said arm as the tension of said spring increases during the opening movement of the door. 25

2. In combination with a wall having a doorway therein and a refrigerating room door for closing said doorway, said door being hinged at one vertical edge thereof to an adjacent portion of said wall so as to facilitate opening and closing of the door, and said door being of substantial thickness and being hinged in such a manner that a substantial portion of its thickness projects beyond the hinge axis whereby the plane of one face of the door is offset substantially relative to the plane of said wall, and a door closer comprising an axially vertical shaft mounted on said wall adjacent the hinged edge of said door, an arm carried by said shaft and extending laterally therefrom and crosswise of said portion of 40 the thickness of the hinged edge of the door which projects beyond said hinge axis, said arm being of such length as not to project substantially beyond said offset face of the door, and spring means tending to turn said arm in a direction 45 to cause the same to apply pressure to said projecting door edge portion to thereby close the door, said door closer being, in effect, housed in the corner formed by the hinged edge of the door and the wall, whereby the closer is substantially prevented from causing injury to persons 50 and also protected from injury by extraneous forces. 35

WILLIAM J. KEENE.

CERTIFICATE OF CORRECTION.

Patent No. 2,102,322.

December 14, 1937.

WILLIAM J. KEENE.

It is hereby certified that error appears in the printed specification of the above numbered patent requiring correction as follows: Page 2, second column, line 18, claim 1, for the word "roller" read means; and that the said Letters Patent should be read with this correction therein that the same may conform to the record of the case in the Patent Office.

Signed and sealed this 22nd day of February, A. D. 1938.

(Seal)

Henry Van Arsdale,
Acting Commissioner of Patents.
